[57] CLAIM

The ornamental design for a mixing bowl, as shown and described.

DESCRIPTION

FIG. 1 is a top right front perspective view of a mixing bowl showing our new design;

FIG. 2 is a cross-sectional view thereof taken through Line 2—2 of FIG. 4;

FIG. 3 is a rear elevational view thereof;

FIG. 4 is a top plan view thereof;

FIG. 5 is a front elevational view thereof;

FIG. 6 is a bottom plan view thereof; and,

FIG. 7 is a side elevational thereof; the opposite side being a mirror image.

FIG. 1

FIG. 2

FIG. 3

FIG. 6

FIG. 7
